UNITED STATES PATENT OFFICE.

JAMES P. HOOPER, OF RUXTON, MARYLAND, ASSIGNOR TO JAMES P. HOOPER MANUFACTURING COMPANY, OF BALTIMORE, MARYLAND, A CORPORATION OF MARYLAND.

APPARATUS FOR PRODUCING THREADS.

Application filed February 23, 1922. Serial No. 538,734.

To all whom it may concern:

Be it known that JAMES P. HOOPER, a citizen of the United States, residing at Ruxton, in the county of Baltimore and 5 State of Maryland, has invented certain new and useful Improvements in Apparatus for Producing Threads, of which the following is a specification.

This invention relates to an improved apparatus for producing threads from viscose 10 or equivalent substances.

One object of the invention is to provide an improved structure whereby the viscose solution may be ejected in the form of 15 threads by centrifugal force.

Another object is to combine with a centrifugal distributor or spinneret an improved structure for supplying a setting solution to act upon the ejected threads.

20 A further object is to provide a structure that combines a centrifugal distributor or spinneret with means for forming a wall of setting solution into which the threads are directed and which are so related as to provide an air gap across which the threads will extend in passing from the ejector means to the setting solution, and

25 Another object is to provide an improved construction of spinneret embodying a series of radial needles whereby through centrifugal force to direct the viscose or other substance along the needles and eject the same in fine threads into a setting solution.

30 With the above, and other objects in view, the invention is illustrated in the accompanying drawing, wherein.—

Fig. 1 shows an apparatus embodying the 40 invention,—the structure being shown in vertical section.

Fig. 2 illustrates an enlarged sectional detail through a portion of the distributor or spinneret to show the means for retaining 45 the radial needles in place, and

Fig. 3 shows an enlarged detail of the spinneret,—the view being an inverted view or a view looking up into the spinneret-chamber from which the needles 50 radiate.

Referring to the drawing the numeral 5, designates a supporting frame in which a bearing block 6 is sustained and through

which a vertical spindle 7 extends. This spindle is tubular in form and therefore 55 has a central vertical passage 8.

A pulley 9, is provided on the vertical spindle whereby to rotate the same.

To the lower end of the spindle I screw 60 a circular shell 10 having a depending annular wall 11 and an inner depending annular flange 12 which is of less depth than said annular wall.

The annular wall 11 of the shell is provided with a series of small perforations 65 or nozzle-openings 13 which extend from the inner to the outer side of said wall.

Through each of the perforations or nozzle-openings 13 I project a thin needle 14 so that a series of radially-projecting 70 needles are provided all the way around the shell.

These needles have their inner ends extending through perforations 15 that are provided through the inner depending annular flange 12, which perforations 15 are aligned with the centers of the perforations or nozzle-openings 13 so that the needles will pass through the nozzle-openings 13 but leave an annular space in each opening 80 around the needle.

The extreme inner ends 16 of the needles terminate in a circular row around the inner circumference of the flange 12 and are engaged by means that will presently be 85 described.

The lower side of the shell 10, is closed by a circular plate 17 whose periphery seats against the rim-edge of the shell and which is held in place by means of a screw 18, which passes through the plate; extends upwardly across the chamber 19 that is formed by the shell and plate, and the upper end of this screw 18 screws into the lower end of the passage 8 in the spindle.

The screw 18 has a central passage 20 and a plurality of lateral outlets 21 which open into the annular chamber 19.

Around the screw I provide a ring or collar 22 which latter seats on the plate 17 and whose vertical thickness is such that when the plate is seated against the shell flange the upper side of the collar 22, will press upwardly against the inner ends 16 of the needles and by springing or pressing the latter upwardly will rigidly retain

those needles in place in the openings 15 of the annular flange.

From the foregoing explanation it will be understood that the vertical passage 8 of the spindle 7, communicates at its lower end with the chamber 19 that is formed by the shell 10 and the plate 17,—the communication between said passage 8 and chamber 19 being by means of the screw-passage 20 and lateral outlets 21.

It is therefore to be understood that the shell 10 and plate 17 together form a chambered head and that said head is carried on the lower end of the spindle and is therefore revolved with the latter. As the outlets or nozzle-openings 13 are located in the vertical flange of the shell and the needles 14 extend horizontally therethrough, said needles will revolve in a horizontal plane.

The shell 10 and the circular plate 17 together form a chambered head which latter revolves in a horizontal plane because it is carried on the lower end of the rotating vertical spindle.

Around the head and the needles projecting therefrom there is provided a shell 23 which has a depending circular wall 24 whose inner side is spaced from the ends of the needles 14. At the upper side of this shell 23 I provide an annular distributor-chamber 25 with a supply-pipe 26 at one side of the latter, whereby a setting solution may be continuously supplied to the chamber.

The distributor chamber extends about the spindle 7 and is located in a plane above the rotary head.

Between the rotary head and the distributor-chamber 25, I preferably locate a baffle-plate 27. In the present instance this baffle-plate has the form of a disk whose upper side is somewhat convex in that its annular rim edge 28 curves downwardly and outwardly toward the inner circumference of the circular shell wall 24 but is spaced therefrom.

In the present instance the baffle-plate 27 is illustrated as carried on the spindle 7, and while certain advantages may be gained by thus mounting the baffle, because rotary motion will be imparted thereto, it is not essential that this baffle be rotated.

Below the shell 23 I show a funnel 29, into which the lower edge of the circular wall 24 extends and directly over which the rotary head is located.

Beneath the funnel I diagrammatically illustrate a reel 30 for a purpose that will presently be explained.

The upper end of the spindle 7, registers with a supply tube 31 so that the viscose or equivalent substance may be discharged from said tube 31 into the vertical passage 8 of the spindle.

The operation of the apparatus is as follows:

Viscose, or equivalent solution, is supplied to the passage 8 of the spindle from the lower end of which it flows through the passages 20 and 21 of the screw and then into the chamber 19 of the rotary head.

At the same time a setting solution is continuously fed through pipe 26 into the distributor chamber 25 and from the latter said solution drops onto the upper convex side of the baffle-plate 27. If the baffle-plate is carried by and revolves with the spindle 7, as I prefer it should, the setting solution will be given a whirling motion as it leaves the rotating baffle and passes downwardly through the narrow gap 32 between the periphery of the baffle and the inner side of the circular shell-wall 24.

The setting solution flows down the inner side of the shell wall and crosses the plane through which the horizontally-rotating needles travel.

This downwardly-flowing wall of setting solution does not contact with the ends of the radial needles 14, but an air-gap 33 or space is maintained between the needle-ends and said solution.

As the head 10—17, revolves rapidly with the spindle 7, the viscose solution in chamber 19 is subjected to the centrifugal force set up by the rotation and caused to flow outwardly along the radial needles 14 and discharged from the ends thereof in the form of fine threads.

These threads upon leaving the needle-ends extend across the air-gap 33 before entering the downwardly-flowing setting solution and while I am not at this moment prepared to state just what effect the air-gap has on the thread, I have found that the strands ejected from the needle ends, when the air-gap is omitted, are broken off into short lengths whereas by providing that gap the strands are ejected in the form of long threads.

As the threads enter the setting solution their speed of rotation is slowed down with respect to the rotating head so that a twisting together and a simultaneous drawing out of the threads takes place.

The twisted threads are then directed down, through the funnel 29 and may be wound on a reel 30 below or subjected to a further treatment if desired.

Having described my invention, I claim,—

1. A mechanism for forming threads including a plurality of needles, revolving means for rapidly moving the needles through a circular path and means for supplying a thread-forming solution to said needles as they move to be ejected by centrifugal force.

2. A mechanism for forming threads including a rapidly rotating member having

- needles projecting therefrom and means for supplying a thread-forming solution to said needles as they travel with the said member to be ejected therefrom by centrifugal force. 70
3. A mechanism for forming threads including a rapidly rotating member carrying a plurality of needles which project therefrom and means at the axis ends of the needles for supplying a thread-forming solution to the needles as they travel with the rotating member whereby to eject the solution by centrifugal force. 75
4. A mechanism for forming threads including a plurality of needles, means for rapidly moving the needles through a circular path, means for supplying a thread-forming solution to the needles as they travel to eject the solution by centrifugal force and form a series of threads, and means for subjecting the threads to the action of a setting medium after they have left the needle-ends. 80
5. A mechanism for forming threads including a rapidly rotating member having needles projecting therefrom, means for supplying a thread-forming solution to said needles as they travel with the rotating member whereby to eject the solution by centrifugal force and form threads and means about the ends of the needles for a setting solution into which the threads ejected from the needles may pass. 85
6. A mechanism for forming threads including a hollow spindle, a chambered head carried by and communicating with the hollow spindle said head having thread-forming openings therein, means for rapidly revolving the head to centrifugally eject material therefrom, an annular shell about the head and spindle, means for continuously supplying a thread-forming solution to the spindle and head, means for continuously supplying a setting solution to the shell and means in the shell above the head for causing the setting solution to flow in an annular stream down past the head. 90
7. A mechanism for forming threads including a rotatable head having a series of circumferential openings, needles carried by the head and extending through said openings, means for supplying a thread-forming solution to the head, means for revolving the head and needles to centrifugally eject the solution along the needles and form threads, and means for subjecting the threads to the action of a setting element. 95
8. A mechanism for forming threads including a head sustained to rotate in a horizontal plane said head having a series of circumferential openings, needles passing freely through said openings and radiating from the head, means for supplying a thread-forming solution to the head, means for revolving the head and needles to cause the liquid to pass through said openings, travel along the needles and discharge from the latter in the form of threads and means for subjecting the threads to the action of a setting element. 100
9. A mechanism for forming threads including a head having a series of circumferential openings, needles passing through said openings and radiating from the head, means for supplying a thread-forming solution to said head, means for revolving the head and needles to eject the solution by centrifugal force along and from the needles and means for directing the flow of a setting solution in a plane which crosses the ends of the needles. 105
10. The combination with a vertical hollow spindle, of a chambered head carried by and communicating with the interior of the spindle said head having a series of circumferential openings, needles radiating from the head at said openings, means for rapidly revolving the head to set up a centrifugal force, means for supplying a thread-forming solution through the spindle to the head to be thrown centrifugally through the openings of the latter and conveyed by the needles, and means around the needles for maintaining a wall of setting solution to receive the strands ejected from the needles. 110
11. The combination with a vertical hollow spindle, of means for rapidly revolving the same, a chambered head carried by the spindle and communicating with the interior of the latter said head having a series of circumferential outlets, needles radiating from and revolving with the head at said outlets, means for supplying a thread-forming solution to the head through the spindle to be ejected by centrifugal force from the needles, a shell about the outer ends of the needles, means for supplying a setting solution to the shell and means in the shell for directing the flow of setting solution downwardly adjacent to the ends of the needles. 115
12. The combination with a vertical hollow spindle, of means for rapidly revolving the same, a chambered head carried by the spindle and communicating with the interior of the latter said head having a series of circumferential outlets, needles radiating from and revolving with the head at said outlets, means for supplying a thread-forming solution to the head through the spindle to be ejected by centrifugal force from said needles, a shell about the outer ends of the needles, a baffle in the shell above the needles and means for supplying a setting solution to the shell above the baffle. 120
13. The combination with a hollow spindle, of means for rapidly revolving the same, a chambered head carried by the spindle and communicating with the interior of the latter said head having a series of circumferential outlets, needles radiating from 125
14. The combination with a vertical hollow spindle, of means for rapidly revolving the same, a chambered head carried by the spindle and communicating with the interior of the latter said head having a series of circumferential outlets, needles radiating from 130

4
and revolving with the head at said outlets, a shell about the outer ends of the needles, means for supplying a thread-forming solution to the head and needles, to be ejected 5 from the needles by centrifugal force, a baffle in the shell and carried by and rotating with the spindle and means for supplying a setting solution to the shell.

14. A device for forming threads including 10 a series of needles, means for moving the needles through a circular path to create a centrifugal force, means for supplying a thread-forming solution to said needles, a shell about the needles, means for supplying 15 a setting solution to the shell and a baffle in the shell between the solution-supply and the needles.

15. A device for forming threads including 10 a series of needles, means for moving

the needles through a circular path to create 20 a centrifugal force, means for supplying a thread-forming solution to said needles, a shell about the needles, means for supplying a setting solution to the shell and a baffle in the shell between the setting solution entrance and the needles. 25

16. A device for forming threads including 30 a series of needles, means for moving the needles through a circular path to create a centrifugal force, means for supplying a thread-forming solution to said needles, a shell about the needles, means for supplying a setting solution to the shell and a rotating baffle in the shell between the setting-solution entrance and the needles said baffle having 35 a curved rim.

In testimony whereof I affix my signature.
JAMES P. HOOPER.
